UNITED STATES PATENT OFFICE.

GEORGE EDWARD WINDELER, OF STOCKPORT, ENGLAND, ASSIGNOR TO GENERAL ELECTRIC COMPANY, A CORPORATION OF NEW YORK.

FUEL-INJECTOR.

1,157,273.

Specification of Letters Paten^t.

Patented Oct. 19, 1915.

Application filed May 22, 1914. Serial No. 840,252.

To all whom it may concern:

Be it known that I, GEORGE E. WINDELER, a subject of the King of Great Britain, residing at Stockport, county of Cheshire, England, have invented certain new and useful Improvements in Fuel-Injectors, of which the following is a specification.

The present invention relates to fuel injectors or pulverizers for spraying oil into the combustion spaces of internal combustion engines, and in particular to those operating on the high compression cycle wherein the high temperature of the air compressed in the working cylinder is utilized 15 to ignite the fuel.

The most common form of injector for such purposes comprises a casing, a plurality of perforated washers that are separated one from the other by spacers, the 20 perforations being staggered, and a needle valve that extends through the washers and is seated on the casing. Fuel is admitted to the casing at some point preceding the first washer so that it must pass through perforations in all of the washers before entering 25 the combustion chamber. These injectors are placed in a vertical position and the fuel discharged by the pump is supposed to be caught by the first washer and be held thereby by capillary attraction until required.

At times the fuel thus admitted to the casing splashes on the side walls thereof above the washers and is held there by adhesion until a serious accumulation takes place when it 35 is liberated and falls on the first washer and when the needle valve is opened is carried by the blast air into the engine resulting in an abnormal increasing of pressure within the cylinder, and violent knocking takes 40 place accompanied by overheating and a dirty exhaust. The more viscous the fuel the more noticeable is the trouble. It is especially true of very high speed engines and is more in evidence on small engines than on 45 large ones.

The object of my invention is to provide a fuel injector or pulverizer in which the objections above referred to are obviated, and this by a simple means.

For a consideration of what I believe to be novel and my invention, attention is directed to the accompanying description and claims appended thereto.

In the accompanying drawing which illustrates one of the embodiments of my invention Figure 1 is a vertical section of my in-

proved injector or pulverizer; Fig. 2 is a plan view of the anti-splashing device; Fig. 3 is an inverted plan view of same, and Fig. 4 is an axial section through the anti-splash- 60 ing device.

5 indicates the cylinder head of an internal combustion engine, and directly below the head is the combustion chamber. The head is provided with an opening and 65 mounted therein is the casing 6 of the fuel injector or pulverizer. This casing is provided with a conical end that is seated pressure tight in the head. The lower end of the casing is provided with a nut 7 to hold 70 the flame plate 8 in place. The casing is provided with an outlet 9 and alined therewith is a needle valve 10.

Surrounding the valve and suitably centered within the casing is a sheath 11 and 75 to the lower end of the sheath is attached a nut 12 having longitudinally extending passages 13 through which fuel and oil in atomized condition flow when the needle valve is open.

Surrounding the sheath are perforated washers 14 which are separated by spacers 15. These spacers may be formed integral with the washers or not as desired. Each washer is provided with a plurality of holes, 85 the holes in one washer being offset from those in the other so that the fuel particles will be finally divided in their passage to the combustion chamber.

Situated above the upper washer is an 90 anti-splashing device for preventing the fuel from being deposited on the inner wall of the casing 6 where it might collect to an objectionable amount. In other words, the anti-splashing device acts to confine the fuel 95 admitted to the injector to a certain definite region, *i. e.* the chamber 16, and prevent it from being splashed or smeared over the inner wall on the casing above the upper washer where it might collect and be retained during several firing strokes of the engine, and which when it did enter the combustion space would give rise to an undue increase in pressure, cause knocking of the piston, overheating, and a dirty exhaust. 100 This anti-splashing device comprises a disk 17, which is shown enlarged in Figs. 2 to 4. It is provided with a number of through ports 18 of which 3 are shown in the present instance. These ports diverge rather rapidly 110 toward the outlet as indicated more particularly in Fig. 4. The object in diverging the

ports is to increase the velocity of the compressed or blast air used to inject fuel into the combustion chamber against the compression pressure. The disk makes an easy fit with the inner wall of the casing, and is held in place by a collar 19 carried by the sheath 11. This collar is provided with ports or passages that correspond in shape and position with those in the disk. The 10 disk 17 also acts as an abutment for the washers 14, and when the nut 13 is seated as shown it holds all the washers and the disk in place. In the side of the casing is a fuel supply conduit 20 that communicates 15 with the pipe leading from the fuel pump. 21 indicates a conduit for admitting compressed or blast air to the casing at a point above the anti-splashing device. This air is under very high pressure. It is not uncommon 20 to use pressures from 800 to 1100 lbs. per square inch for this purpose. Of course, whatever this pressure may be, that of the fuel supply must be superior. The fuel is delivered to the injector during the 25 period that the needle valve is closed, the latter opening once for each firing of the cylinder which it supplies. The fuel passes through the conduit 20 and is discharged upon the upper disk where it is 30 confined until the needle valve is opened. As soon as this happens, air from the conduit 21 rushes through the ports 18 in the anti-splashing device and striking the oil below carries it through the holes in the 35 disks and finally discharges it through the outlet 9 into the combustion chamber.

The valve may be operated in any suitable manner. As shown it passes through the top casing 25, and is provided with a head 26 40 that is normally forced downward by the coiled compression spring 27. On the valve is an abutment comprising adjustable nuts 28, the latter engaging washers 29. The valve is opened against the tension of the 45 spring by the lever 30, the latter being moved by a cam on the cam shaft in the usual way.

It will be noted in my improved construction that the fuel instead of being delivered 50 to a large chamber where it is relatively unrestricted, is delivered to a chamber where it is confined, and that when the needle valve is opened, the high pressure blast air strikes the body of fuel at a plurality of points, and 55 forces it in a finely divided state through the outlet 9 into the combustion chamber. It will also be noted that the blast air has acquired a considerable velocity before it strikes the oil and that no opportunity is 60 afforded for the fuel to be pocketed and hence allowed to remain in the injector after the needle valve opens.

In accordance with the provisions of the

patent statutes, I have described the principle of operation of my invention, together 65 with the apparatus which I now consider to represent the best embodiment thereof; but I desire to have it understood that the apparatus shown is only illustrative, and that the invention can be carried out by other means. 70

What I claim as new and desire to secure by Letters Patent of the United States, is:—

1. A fuel injector comprising a casing having an outlet, a needle valve, a series of 75 perforated and spaced washers, a member supported by the casing adjacent the outlet and having passages for fuel and air that discharge into the outlet, a conduit delivering fuel to the top of the upper washer, and a conduit admitting compressed air to the 80 casing, in combination with an anti-splashing device which is situated in the casing between the fuel and air conduits and in close proximity to the first of the series of washers so as to form a chamber into which the fuel 85 is delivered, said anti-splashing device having an opening through which compressed air passes before it strikes the fuel.

2. In a fuel injector, the combination of a 90 casing having an outlet, a plurality of perforated washers mounted within the casing, spacers between the washers, a needle valve that extends through the washers and spacers, a seat for the valve carried by the casing, an anti-splashing device comprising 95 a disk located in front of and separated from the first washer by a chamber adapted to receive fuel, said disk having through ports, a conduit for discharging fuel into said chamber, and a conduit for admitting 100 high pressure air to the casing on the opposite side of said device from the fuel receiving chamber.

3. In a fuel injector, the combination of a 105 casing having an outlet a tubular sheath located in the casing, a nut secured to the sheath and provided with passages extending toward the outlet, a plurality of perforated washers mounted on the sheath and separated one from the other, a needle valve that extends through the sheath, a seat for the valve carried by the casing, an anti-splashing device comprising a disk located in front 110 of the first washer and provided with ports that diverge toward the washers, a conduit for admitting fuel to the region between said disk and said first washer, and a conduit for admitting high pressure air to the casing on the inlet side of the disk.

In witness whereof, I have hereunto set 115 my hand this 8th day of May, 1914.

GEORGE EDWARD WINDELER.
